[57] CLAIM

The ornamental design for an electronic copying machine, as shown.

DESCRIPTION

FIG. 1 is a top, front and left side perspective view of an electronic copying machine, showing our new design;
FIG. 2 is a front elevational view thereof;
FIG. 3 is a top plan view thereof;
FIG. 4 is a right side elevational view thereof;
FIG. 5 is a left side elevational view thereof;
FIG. 6 is a rear elevational view thereof;
FIG. 7 is a bottom plan view thereof;
FIG. 8 is an enlarged cross-sectional view thereof taken on line 8—8 in FIG. 2; and,
FIG. 9 is an enlarged cross-sectional view thereof taken on line 9—9 in FIG. 4.

FIG. 1

FIG. 2

FIG. 3

FIG. 4
